UNITED STATES PATENT OFFICE

ELPHA E. BAILEY, OF DENVER, COLORADO

METALLIC SOCKET AND MOLD FOR AMALGAM DIES

Application filed May 15, 1930. Serial No. 452,625.

This invention relates to improvements in the art of making and accurately seating amalgam dies in models and relates more particularly to the construction of the socket employed.

It is the object of this invention to produce a socket by means of which an amalgam die can be accurately and removably seated in a model for the purpose of making restorations, which, when completed in the model, will fit the original accurately and which is particularly valuable in master model and opening the bite cases.

In inlay and bridge work, it is customary to make amalgam dies of the teeth on which work is to be done and to mount the dies in master models, that in turn are mounted in articulators and these dies and models are used in making restorations which, when completed, will fit the originals accurately providing the dies and models have been carefully made.

The usual method of procedure is to cut the cavity preparations, after which a shell containing an impression compound is inverted over the prepared tooth and after the compound has set the shell is combined with a ferrule and the two used as a mold for making an amalgam die. After the die has hardened, it is removed and the root portion thereof cut down to a tapered irregular polygon. An impression is now taken of the tooth that is worked on by means of an impression compound and after this is removed the amalgam die is placed into the socket in the impression compound and will fit therein due to the fact that it is the same shape as the tooth from which the impression was taken. Plaster is now used to make a master model and the plaster is poured around the root portion of the die and therefore when the master model is removed the die will occupy a position therein that corresponds to the position of the tooth in the mouth. The method outlined, although it is quite widely practiced, does not give accurate results and it therefore becomes necessary to do a considerable amount of fitting.

In the employment of my invention, a slightly different method is used and in order

to bring out the objects and advantages of the present invention, I will describe the operation as practiced by me.

The tooth is first provided with the cavity after which an impression of the cut end of the tooth is taken by means of a shell containing an impression compound. The shell is then combined with my improved socket by means of wax and the two are then embedded in plaster so as to form a mold and this is then filled with amalgam. After the amalgam has set the plaster is broken and the shell and socket removed after which the shell is removed. The amalgam die can now be removed from the socket if desired. The socket tapers towards one end and is noncircular and is preferably formed with a cross section that is an irregular polygon so that the die can be reinserted in one position only. After the die has been made, heavy foil is swedged over the cavity and stiffened with low fusing solder, so as to form a temporary inlay or adaptation. With the temporary inlay in place, an impression is taken by means of impression compound and when this is removed the inlay will adhere to the compound and form the bottom of the cavity. The amalgam die is now inserted into the cavity and adjusted to fit the inlay and it will therefore correspond exactly to the position of the tooth. With the socket in place on the root portion of the inlay, plaster is poured about the socket in the preparation of the master mold. When the master mold is removed, the socket will be retained therein and the amalgam die can therefore be removed and replaced at will and due to the fact that the socket is an irregular polygon or is noncircular, the die can be replaced in one position only, and will be held accurately whenever it is in position.

Having thus briefly described the invention and the manner in which it is used, the same will now be described in greater detail, and with more particularity and for this purpose, reference will now be had to the accompanying drawing in which:

Fig. 1 shows a side elevation of a tooth that has been provided with a cavity preparation; Fig. 2 shows the same tooth in the process

of having an impression made of the cavity; Fig. 3 shows the shell with the impression therein and my improved socket assembly and invested in plaster in position to receive the amalgam and molding the die;

Fig. 4 shows the tooth provided with a temporary inlay and in the process of forming an impression in a piece of impression compound;

10 Fig. 5 shows the amalgam die in position in the impression and the root portion seated in the sleeve which is embedded in a master model;

15 Fig. 6 shows the master model, partly broken away and shows the improved socket in place therein;

Fig. 7 shows the socket and the amalgam die separated from each other; and

20 Fig. 8 shows one way of removing the amalgam die from the socket.

In the drawing reference numeral 1 designates a tooth that has a cavity preparation 2 and 3 represents the gum or the jaw of the person to whom the tooth belongs. After 25 the cavity has been prepared, a shell 4 is partially filled with impression compound 5 and inverted over the tooth. After the compound has set, the shell is removed and combined with my improved socket 6 by a few drops 30 of wax and the shell and socket are then invested in plaster 7. The socket and shell are now filled with amalgam and after the mercury has been squeezed out, the amalgam die 8 is allowed to harden after which the plaster 35 is broken away and the shell removed. A small bolt 9 is provided which passes through the socket and the amalgam die is formed about this bolt which serves to hold it in place in the socket.

40 A temporary inlay 10 is now formed by swedging heavy foil into the cavity and then stiffening the same with low fusible solder. After the temporary inlay has been formed, a piece of impression compound 11 is introduced between the teeth and the jaws clamped thereon so as to form an impression of the tooth. When the compound has set, it is removed and the inlay 10 remains in the cavity and forms the bottom thereof. The 45 amalgam die 8 is now put into place in the cavity as shown in Fig. 5 and is fitted into the inlay after which the socket is invested in a plaster master model 12. The head of the bolt 9 is left exposed and the die can be removed only after this bolt has been removed and the bolt can be inserted only after the die has been brought back to the exact position so that the die will be accurately seated.

50 For convenience in removing the die from the socket, the latter has been provided with projections 13 that can be engaged by the end of the jaw 14 of a pair of pliers, whose other jaw has its end bent as indicated by 15.

55 In Fig. 7, the socket and die have been shown separated and the root portion of the

die has been designated by reference numeral 16. Particular attention is called to the fact that the socket is tapered and has a non-circular unsymmetrical cross section. It may have the shape of an irregular polygon as 70 shown, or it may have curved sides, but it should not be circular because the die should fit in a single rotary position only and therefore the cross section should be unsymmetrical. I consider that the shape of the socket is 75 of vital importance because the die must be firmly held in a single position only, and must be readily removable and this can be accomplished only by making the socket with an unsymmetrical cross section and slightly 80 tapered and I consider that such a socket for the purpose specified as well as a master mold having such a socket embedded therein constitutes my invention.

Having described my invention what I 85 claim as new is:

1. A metallic socket for use in molding the root end of an amalgam die to facilitate the accurate seating of the die in a master mold, said socket comprising a tubular tapered 95 metal member whose wall is of substantially the same thickness at all points of unsymmetrical cross section and open at both ends.

2. A metallic socket for use in molding the root end of an amalgam die to facilitate the 95 accurate seating of the die in a master mold, said socket comprising a tubular tapered metal member whose wall is of substantially the same thickness at all points whose cross section is an irregular polygon and which is 100 open at both ends.

3. A tapered metallic socket for use with a master model of plaster of Paris and adapted to be embedded therein, said socket having a wall whose thickness is substantially the 105 same at all points and whose cross section in a plane substantially perpendicular to the longitudinal axis of the socket is a closed figure of unsymmetrical shape, the smaller end of the socket being within the material of the 110 mold and the larger end exposed.

4. A tapered metallic socket for use with a master model of plaster of Paris and adapted to be embedded therein, said socket having a wall whose thickness is substantially the 115 same at all points and whose cross section in a plane substantially perpendicular to the longitudinal axis of the socket is a closed figure of unsymmetrical shape, the smaller end of the mold and the larger end exposed, the outer surface of the socket having projections 120 for the purpose of anchoring it in the material of the model.

125 In testimony whereof I affix my signature,
ELPHIA E. BAILEY.
